UNITED STATES PATENT OFFICE

GEORGE A. EYNON, OF PARMA, OHIO

CARBURETOR

Application filed January 11, 1930. Serial No. 420,028.

This invention relates to improvements in carburetors and has for its principal object to provide a carburetor which will give at ordinary driving speeds a maximum fuel economy and at full throttle will give a maximum of power.

A further object is to provide such a carburetor with a more efficient idling arrangement whereby the fuel mixture may be adjusted after being mixed and may be admitted on the engine side of the throttle. Other and more specific objects will appear as the description proceeds.

Referring to the accompanying drawings, Fig. 1 is a schematic vertical section of my improved carburetor; Fig. 2 is a fragmentary section on line 2—2 of Fig. 1; Fig. 3 is a fragmentary section on line 3—3 of Fig. 1; Fig. 4 is a detail section of the lower end of the adjusting needle 21; Fig. 5 is a fragmentary section on line 5—5 of Fig. 1; Fig. 6 is a fragmentary section on line 6—6 of Fig. 1; Fig. 7 is a fragmentary vertical section taken at right angles to the showing in Fig. 1; and Fig. 8 is a vertical section on line 8—8 of Fig. 7.

My improved carburetor, as best shown in Fig. 1, includes the conventional float chamber F and air inlet A of usual construction, a mixing chamber M including the conventional venturi 44, a throttle valve 37 and a conduit C continuous with the mixing chamber M and adapted to be connected to the intake manifold of an internal combustion engine by any suitable means (not shown). The float chamber F is provided with an inlet 12 for fuel which is controlled by a needle valve 14 seating in the bore 13, held in position by bracket 15 secured by screws 16 and controlled by the float 11 which is pivoted at 17 by means of an arm 20 attached at 19 and provided with a boss 18 adapted to contact with the needle 14.

The air inlet A comprises the usual tubular portion 45 having a butterfly valve 47 journaled in the tubular portion by means of a shaft 46 containing a slot through which the butterfly valve 47 extends and in which the same is secured and controlled by a lever 50 46^a secured in fixed relation to said shaft 46.

Extending into the mixing chamber M, I have shown concentric tubes 50 and 51 provided with restricting means 49 and 52 respectively. While I have shown these tubes concentric, it is evident that they may be placed side by side if desired. As shown, the tube 50 communicates directly with the float chamber F and has a fixed dimension determined by the restricting means 49. The tube 51 communicates also with the float chamber through the opening 22 but this opening is adjustably controlled by the needle 21 provided with a threaded portion 23 which extends through the upper wall of the float chamber and is provided with a knurled head 24. The tube 51 communicates with the chamber S, the chamber into which fuel from the mixing chamber is directed through the bore 22. Also communicating with the chamber S is a passage 26 having an enlarged lower end forming a well and a smaller passage 26^a continuous with said well and communicating through the throttle rod 40 with the atmosphere in a manner to be hereinafter described.

The well forming a part of the passage 26 should be considerably larger than the portion 26^a thereof and may be of any desired shape, that shown, circular or any other desired. The construction of the needle 21 is shown in detail in Fig. 4 and includes a bore 21^a passing radially through the needle, a large bore 21^b extending longitudinally and connected with the bore 21^a by a restricted bore 21^c, whereby the fuel supply from the float chamber into the chamber S is never entirely cut off.

The idling mechanism consists of a well 54 communicating by an opening 27 with the float chamber through a restricting plug 27^a. This well 54 is in unrestricted communication with the atmosphere through an opening 54^a at the upper end. Extending into the well 54 is a tube 53 communicating with a mixing chamber 29 and provided with a restricting plug 48. Above the restricting plug 48 is an opening 34 which communicates with the atmosphere as best shown in Fig. 3. In the mixing chamber 29 is an opening 28 which communicates with the at-

mosphere as best shown in Fig. 6. The mixing chamber 29 communicates with the conduit C through two ports 35 and 36. When the throttle is closed, the port 36 is rendered substantially or entirely inoperative as indicated in Fig. 1. This port 36 is employed only when the throttle is opened somewhat and the port 35 is relied upon for idling. A needle 30 is threaded through the casting as shown at 32 and provided with a knurled head 31 by means of which the same may be rotated to adjust the effective size of the opening 35.

The passage 26 extends to the journal 38 in which the shaft 40 is rotatable and communicates with the bore therein in which said shaft rotates. A second bore 39 in said journal also communicates with the bore in which the shaft 40 is journaled and a notch 40^a is provided in the shaft 40 and connects the passages 26 and 39 when the throttle is closed and until the same has been opened to about 35°, corresponding substantially to half throttle. It will be evident that after the throttle is open, the air which passes through 39 into 26 will be gradually reduced.

Operation

Assuming the throttle in the position shown in the drawings, the carburetor will be in idling position. The suction produced by the engine will communicate with the port 35 and cause fuel to flow from the float chamber F through the opening 27 into the well 54, into the tube 53 and through the restricted passage 48. At the same time, air will flow into the opening 34 and mix with the fuel coming through the passage 48. This mixture will flow into the mixing chamber 29 and there be further mixed by the introduction of air through the passage 28. These passages are proportioned so as to be of such size that a desirable mixture is obtained. The amount of air fuel mixture admitted through the port 35 may be adjusted by means of the needle 30. The well 54 will at the time of starting the motor have a fuel level as high as that in the float chamber and this extra supply of fuel provides for the demands of starting.

When the throttle is opened, the port 36 will be uncovered and suction from the motor will be transmitted to the mixing chamber 29 and will suddenly increase the suction through the tube 53 to draw more fuel from the idling supply and the reserve fuel in the well 54 may be relied upon to supply the fuel demand caused thereby. At the same time, the engine suction communicates with the tube 50 and causes a jet of fuel to flow from the float chamber into the mixing chamber through the restriction 49. Thus through the tube 50 a constant supply of fuel proportionate to the engine suction is

supplied to the mixing chamber. At the same time, the engine suction is communicated to the tube 51 and during the first 35° of opening of the throttle, a mixture of air and fuel will be supplied from the chamber S by fuel entering through the port 22 and air entering through the port 26 communicating therewith. It will be obvious that before the throttle is opened, the fuel level in the passage 26 will be at the level in the float chamber and that consequently a rich mixture will be supplied for starting by reason of the fuel in the well being drawn through the port 27 and opening 25 into the tube 51. As soon as this level is brought down so that the well is empty, there will be air entering through the bore 26 and fuel through the port 22 which will be mixed in the chamber S and drawn through the restriction 25 into the tube 51 and thus delivered to the mixing chamber M. After the throttle is substantially half open, that is, has been opened through about 35°, the air supplied to the passage 26 will have been cut off by the passing of the notch 40^a in the shaft 40 out of register with the port 39 and as a result only pure fuel without air will be delivered through the tube 51 to the mixing chamber. Consequently, it will be seen that up to approximately half throttle, that is, in the ordinary driving ranges, a main jet of fuel will be supplied through the tube 50 and a mixture of fuel and air will be supplied through the tube 51 but that from approximately half throttle to full throttle, fuel only will be delivered through the tube 51 which will result in a richer mixture and consequently increased power. The feature of cutting off the supply of air through port 39 at approximately half throttle results in materially increased power for rapid acceleration and fast driving. The presence of the supply of air through port 39 at normal driving positions gives rise to the maximum fuel economy.

While I have shown openings 28 and 28^a communicating between the mixing chamber 29 and the atmosphere and said mixing chamber and the chamber M respectively, it is to be understood that I may employ either or both of these openings as desired. If both are used the sizes will be proportionally diminished. If only one is used the other will be closed by means of a plug or omitted entirely. In general I prefer to employ the opening 28^a since by so doing I obviate an undesirable sound produced by the rushing of air through the opening.

It will thus be seen that I have provided a carburetor having an efficient idling mechanism, and capable of delivering at ordinary driving positions of the throttle a maximum fuel economy and at positions approaching full throttle a maximum power.

While I have shown one embodiment of

my invention, I wish it understood that the same is merely illustrative and schematic and that I am limited only in accordance with the scope of the appended claims.

5 Having thus described my invention, what I claim is:

1. A carburetor including a mixing chamber, a throttle, an air inlet and a constant level fuel chamber, a main fuel supply nozzle communicating between said constant level fuel chamber and said mixing chamber, an auxiliary fuel supply nozzle communicating with said mixing chamber adjacent said main nozzle, a shaft carrying and controlling said throttle, a notch in said shaft, a passage in said carburetor body to atmosphere intersected by said shaft, a larger passage communicating with said constant level fuel chamber, said first passage and, 10 through a restriction, with said auxiliary fuel supply pipe, said notch being so formed as to open the passage at closed throttle, gradually restrict said passage as said throttle is opened and to substantially close said 15 passage through at least the last quarter of its throw.

2. A carburetor having a mixing chamber, an air inlet and a constant level fuel chamber, a shaft journaled in the body of 20 said carburetor, a throttle carried by said shaft, a main nozzle delivering into said mixing chamber and communicating only with said mixing chamber and said constant level fuel chamber, an auxiliary nozzle delivering into said mixing chamber and connected to an auxiliary fuel chamber, said auxiliary fuel chamber also communicating with 25 said constant level fuel chamber, a passage intersected by said shaft and connected between said auxiliary fuel chamber and outer atmosphere, said shaft embodying means for 30 opening said passage at closed throttle, progressively closing said passage as the throttle is opened at such a rate that same is substantially closed between three fourths 35 and full throttle.

In testimony whereof, I hereunto affix my signature.

GEORGE A. EYNON.
